DETONATOR POUCH

Leonard P. Frieder, Great Neck, N. Y., and Leonard D. Jackson, Colonial Beach, Va.; said Jackson assignor to said Frieder

Application February 10, 1955, Serial No. 487,316

10 Claims. (Cl. 224—17)

Our invention relates to a detonator pouch and more particularly to an improved detonator pouch which protects the wearer against injury from the accidental detonation of a detonator carried in the pouch and which prevents the sympathetic explosion of other detonators in a pouch by the accidental explosion of one of them.

Detonators are employed in demolition work, and the like, for setting off a charge of an explosive such as dynamite, TNT, composition "C," or the like. These detonators each include a charge of a high explosive, such as lead azide, fulminate of mercury, PETN, or the like, housed in a tube formed of copper, aluminum, or other metal. Both electric and percussion type detonators are made. When a blaster is on the job, he carries a supply of detonators in a carrying pouch. The pouches of the prior art are merely bags for convenient carrying of the detonators. They afford no protection to the person carrying the pouch in event of an accidental discharge of the detonators in the pouch. In case of an accidental discharge of a detonator, fragments of the detonator housing tube are driven with great force through the walls of the pouch. Deaths and very serious injuries have resulted from such accidental explosions. When detonators of the electric type explode accidentally, fragments of the wire, along with tiny fragments of metal of the detonator housing, are driven into a bearer's body. Further, accidental discharge of one detonator may cause sympathetic firing of adjacent detonators in the same carrying pouch.

We have invented a detonator pouch which contains the explosion of an accidentally fired detonator, and which prevents sympathetic firing of adjacent detonators in the same pouch. Our pouch is relatively small, compact, and lightweight for the protection which it affords. The material of which our pouch is formed resists penetration by the tiny fragments of metal and wire formed during the accidental explosion of a detonator.

One object of our invention is to provide a carrying pouch for detonators which protects the wearer from injury resulting from the accidental discharge of a detonator housed in the pouch.

Another object of our invention is to provide a carrying pouch for detonators which contains the explosion of an accidentally fired detonator.

A further object of our invention is to provide a carrying pouch for detonators which prevents sympathetic firing of adjacent detonators when one detonator is accidentally fired.

A still further object of our invention is to provide a protective detonator carrying pouch which is compact, small, and lightweight.

Other and further objects of our invention will appear from the following description.

In general, our invention contemplates the provision of a detonator carrying pouch formed of ballistic material which resists penetration by fragments of metal formed during the accidental explosion of a detonator carried therein. Our pouch is so constructed that it contains an

2

accidental explosion of a carried detonator and also prevents sympathetic firing of detonators adjacent an accidentally fired detonator. It includes an outer container, formed of ballistic fabric, within which we dispose for 5 partial removal therefrom an inner flap of ballistic material. On the inner flap we form a number of compartments of ballistic material. Each of these compartments is adapted to contain a detonator. The inner flap is so constructed that it may be partially withdrawn from the 10 container, wrapped about the cartridge compartments, and inserted within the outer container. We secure to the container by any convenient means a cover flap overlapping a portion of the front of the container. We provide our pouch with a novel carrying means which is 15 readily releasable to permit the pouch to fall from the wearer's body.

In the accompanying drawings which form part of the instant specification and which are to be read in conjunction therewith and in which like reference numerals are 20 used to indicate like parts in the various views:

Figure 1 is a perspective view of one form of our detonator carrying pouch showing the manner in which the outer container cover is secured to the front of the pouch.

Figure 2 is a perspective view of the form of our detonator carrying pouch shown in Figure 1 showing the means by which the pouch may be carried on a wearer's body.

Figure 3 is a perspective view of the form of our detonator carrying pouch shown in Figure 1 with the outer container cover open and with the inner flap raised to show the arrangement of the detonators within their respective compartments.

Figure 4 is a sectional view, taken along the line 4—4 of Figure 3, of the form of our detonator carrying pouch 35 shown in Figure 1.

Figure 5 is a sectional view, taken along the line 5—5 of Figure 4, drawn on an enlarged scale, of the form of our detonator carrying pouch shown in Figure 1.

Figure 6 is a fragmentary perspective view, drawn on 40 an enlarged scale, of one type of ballistic material which may be used in our detonator carrying pouch.

More particularly referring now to the drawings, our detonator pouch includes an outer container, indicated generally by the reference character 10, the front 14, bottom 16, back 18, and cover 20 of which are formed of an integral length of material, the nature of which will be described in detail hereinafter. Respective lines of heavy stitching 26 and 28 secure a pair of respective side panels 22 and 24 to the front 14, base 16, and back 18 of the container 10 at its sides. The cover 20 is extended at 30 to overlie a portion of the front 14 when it is in the closed position. Any suitable securing means may be employed to hold the cover 20 in closed position. Conveniently, we secure a number of leather buttons 32 at spaced points 35 along a line adjacent the edge of cover 20 by thread 34. Each of the buttons 32 carries a length of braided cord 36 anchored at one end to a button 32 by means such as a knot or the like. To close cover 20 the lengths 36 carried by buttons 32 engage buttons 38 secured at spaced locations along the length of front 14 by stitching 40. Cover 20 may be closed tightly on the container 10 by 45 passing lengths 36 alternately about respective buttons 38 and 32. It is to be understood that cords 36 and buttons 32 and 38 may be replaced by any other suitable fastening means, such, for example, as snap fasteners, if desired.

If desired, we may form a pocket 42 for carrying a tool, such as an awl or the like, by securing a piece of nylon fabric 44 to side 22 by stitching 46. A flap 48 secured to the top of side 22 by suitable stitching carries a button 50 by means of threads 52. Button 50 carries a length of braided cord 54 which may be wrapped alter-

nately about a button 56 held on fabric 44 by thread 58 and about button 50 to close pocket 42. Cord 54 and buttons 50 and 56 may be replaced by other suitable fastening means, if desired.

We may form a second pocket 60 on side 24 by securing a piece of fabric 62 thereto by stitching 64. A flap 66 suitably sewed to the top of side 24 provides a closure for pocket 60. Respective threads 72 and 74 secure a pair of buttons 68 and 70 to flap 66 and fabric 62. A braided cord 76 carried by button 68 may be wound alternately about button 70 and about button 68 to secure flap 66 in its closed position.

In order to provide a means by which the pouch may be carried, we form a belt 78 from an appropriate material, such as fabric webbing or the like. A pair of fabric pieces 80 and 82 secured to the back 18 of container 10 by respective lines of stitching 90 and 92 retain belt 78 on container 10. One end of belt 78 is formed with a number of spaced longitudinal openings 94. The other end of belt 78 carries an eye 96 which may be passed through an opening 94 when the pouch is to be carried. I secure one end of a shoulder strap 98, which may be formed of textile webbing or the like, to the portion of belt 78 between fabric pieces 80 and 82 by stitching 100. The end of strap 98 remote from stitching 100 passes through the eye 102 of a hook 104 and is secured back along the length of strap 98 by stitching 106. A spring 108 carried by the shank of hook 104 normally closes the hook opening. When the pouch is assembled on the wearer's body, belt 78 passes around the wearer's waist and eye 96 passes through an opening 94 corresponding to the waist size of the wearer. Strap 98 passes over the wearer's shoulder and the hook 104 engages eye 96. It will be appreciated that this means for supporting the pouch on the wearer's body may readily be released to permit the pouch to be doffed by the wearer. To accomplish this, I press spring 108 to open hook 104 and then slip the hook out of eye 96. The end of belt 78 formed with openings 94 falls away from eye 96 and the pouch falls away from the wearer's body.

Referring now to Figures 3 to 5, we fix one end of an inner flap, indicated generally by the reference character 110, along the interior surface of the front 14 of the container 10 by stitching 112. Flap 110 is formed of the same material as container 10 and, in the closed position shown in Figure 5, it includes a front 114, a base 116, a back 118, a top 120, and a front closure portion 122. In this closed position shown in Figure 5, the portion 122 is inserted into the space between front 114 and back 118 of inner flap 110. In the position shown in Figure 3, portion 122 of flap 110 is withdrawn from within the space between front 114 and back 118 to expose a plurality of compartments 124 carried by the back 118 of flap 110. Compartments 124 are formed by a continuous length of flexible ballistic material of a nature similar to that of which container 10 and flap 110 are formed. This length of material is doubled on itself and stitched at spaced points to form vertical lines of stitching 126. It will be seen that adjacent lines of stitching 126 form the length of ballistic material into compartments 124. A pair of vertical lines of stitching 126 between the center compartments 124 secure the respective ends of the length of ballistic material forming compartments 124 to the portion of the material between the center two compartments. A vertical line of stitching 128 secures the length of material forming compartments 124 to the back 118 of flap 110. It is to be understood that the ends of the material forming compartments 124 may, if desired, be disposed at any other convenient location.

In order to provide a means by which detonators carried in the compartments 124 may expeditiously be removed therefrom, we encase each of the respective detonators 130 in a sleeve 132. The detonators 130 are supported at one end in a rubber plug or the like 134 and then inserted in a sleeve 132. Sleeves 132 carrying de-

nators 130 are then placed within compartments 124. The sleeves 132 may advantageously be made of a tightly woven, thin nylon fabric which has a smooth surface so that the sleeves 132 may readily be withdrawn from the compartments 124. We form each of the sleeves 132 with tabs 136 at its upper end by means of which the sleeve and detonator are withdrawn from a compartment 124. Electric detonators are generally supplied in cardboard tubes which house the detonator and the lengths of wire to be used therewith. When these detonators are to be carried in one of our pouches, the explosive charge 130 and plug 134 are removed from the cardboard cylinders, enclosed in sleeves 132, and inserted within the compartments 124. The wire which is to be used with the detonator is left in the cardboard cylinder, and the cylinders are placed one on top of the other between the portion 122 of flap 120 and the front walls of compartments 124. This can be seen by reference to Figure 5 in which we have indicated the cardboard containers by the reference character 138 and the detonator wiring by the reference character 140. It will be understood that when these electric type detonators are stored in our pouch, the size of the pouch must be sufficiently large to house the cardboard cylinders 138 as well as the detonating charges 130. If percussion type detonators are employed, the pouch may, of course, be smaller.

We have found that we may form a fabric having superior explosion containing properties by forming the fabric of a plurality of stacked fabric laminates, each of which is made of yarns formed of continuous, synthetic, filamentary threads spun to a predetermined number of convolutions per unit length. Referring now to Figure 6, the length of fabric making up the front 14, bottom 16, back 18, and cover 20 of our pouch includes a stack of fabric laminates 142. Each of the laminates 142 is made up of yarns including a number of threads. Each of the threads includes a number of continuous filaments of a material such as nylon or the like. We spin the filaments making up a thread of our material to within a predetermined range of percentages of their ultimate elongation. To accomplish this, we place a length of filamentary material of which the threads are to be formed under controlled tension and measure its elongation up to the point at which the filament parts. We have discovered that if we spin the filaments making up a thread to a tension which is within the range of tensions required to produce, respectively, an elongation which is fifty percent of the ultimate elongation and an elongation which is ninety percent of the ultimate elongation of the material, we produce a fabric which has superior resistance to rupture.

When a thread of our fabric is to be made up, we first determine the tension per unit of cross-sectional area required to produce an elongation which is fifty percent of the theretofore determined ultimate elongation of the material. We then determine the tension per unit of cross-sectional area required to produce an elongation which is ninety percent of the ultimate elongation of the material. Each of the threads may include any convenient number of filaments such, for example, as thirty-four. We spin this bundle of filaments on a suitable torsional apparatus, and determine the number of convolutions per unit length of the bundle required to produce an elongation which is fifty percent of the ultimate elongation of an individual filament. We then determine the number of convolutions per unit length required to produce a tension which corresponds to an elongation which is ninety percent of the ultimate elongation of an individual filament. With these two measurements of the number of convolutions per unit length, we form a thread of our explosion-resisting fabric by spinning a bundle of filaments to a number of convolutions per unit length which is within the range determined. It is to be understood that the range of convolutions per unit length should be determined for each sample of material to be used.

When a laminate 142 is to be formed from these threads, a number of threads, such, for example, as five, are cabled to form a weaving end or yarn. We weave these yarns into fabric to form a laminate 142. After we form the laminates 142 we assemble in stacked relationship a number of laminates sufficient to afford the degree of resistance desired. In the fabric shown in Figure 6 we have assembled five such laminates, and have enclosed the stacked laminates in an envelope of fabric 144 which may be tightly woven nylon fabric of a type known to the art.

While our explosion-resistant fabric may include merely an assembled stack of laminates 142, we may, if desired, employ loose basting stitches 148 for holding the laminates 142 in stacked relationship. Alternately, we may employ a fabric of the nature disclosed in our copending application, Serial No. 362,338, filed June 17, 1953, now pending. The fabric disclosed in this said copending application includes a plurality of fabric laminates, similar to laminates 142, which are bonded to one another by spaced bonds formed by interweaving the respective laminates making up the fabric. In the form of our pouch shown we include only five stacked laminates in the material making up the front 14, bottom 16, back 18, and cover 20. Sides 22 and 24, as well as the inner flap 110, also include only five laminates. The length of material making up compartments 124 may conveniently include ten laminates or a double thickness of material each of which thicknesses includes five laminates. It will be understood that the number of laminates included in each of the parts of our pouch may be varied as necessary to provide the required measure of protection. We encase the length of laminated material making up each of the parts of our pouch in a suitable material such as tightly woven nylon fabric similar to the nylon fabric 144. We close the ends of the enclosing fabric 144 by stitching 146 to provide an envelope around the laminated assemblies enclosed thereby.

When our pouch is to be used to store detonators, we open cover 20 and withdraw the portion 122 of flap 120 in the manner shown in Figure 3. For purposes of convenience in loading, we have disposed the stitching 112 securing flap 120 in the interior of the container at a location which permits flap 120 to be partially withdrawn from within the container. In the withdrawn position of flap 120 the compartments 124 are exposed to permit ready loading thereof. When we wish to store detonators of the electric type in our pouch, we remove the detonator charges 130 and mounting plugs 134 from the cardboard carrying cylinders 138. We then insert each of the detonators 130 along with its mounting plug 134 in a sleeve 132 and place sleeves 132 in the respective compartments 124. The wire for each of the respective electric detonators is left in one of the cardboard carrying cylinders 138. We stack cylinders 138 one on top of the other in front of the compartments 124 and insert the portion 122 or flap 120 between the front 114 of flap 120 and the cardboard carrying cylinders 138. We close cover 20 of the container and secure it in its closed position by the lengths of braided cord 36 carried by the buttons 32. The loaded pouch is then assembled on the wearer's body by passing belt 78 about his waist and inserting eye 96 through an opening 94. Shoulder strap 98 passes over one shoulder of the wearer and hook 104 snaps into engagement with eye 96. This carrying arrangement permits the wearer to shed the pouch by merely unlatching hook 104 from eye 96 and permitting the pouch and carrying straps to fall away from his body. In the event one of the detonator charges 130 explodes, penetration of fragments of the metal tube of charge 130 or of fragments of the wire is prevented by the stacked laminates 142 making up the material of which the pouch is formed. The individual compartments 124 prevent sympathetic firing of charges adjacent an accidentally exploded charge. When detonators of the percussion type

are used, no space need be left within the container for cardboard carrying tubes 138.

While we have shown only one form of our detonator pouch, it will be understood that the pouch may take many forms. It may be made to contain as many charges as desired. It may be formed with or without carrying pockets 42 and 60. Any convenient securing means may be substituted for buttons 32 and 38 and braided cords 36. Further, other and different types of carrying means than belt 78 and strap 98 may be employed.

It will be seen that we have accomplished the objects of our invention. We have provided a detonator carrying pouch which prevents injury to the wearer from the accidental explosion of a detonator charge within the pouch. Our pouch is so constructed that it prevents sympathetic firing of adjacent detonator charges to an accidentally fired detonator charge. Our pouch is compact, small, and lightweight. We have provided our pouch with a carrying means which permits the wearer readily to doff the pouch.

It will be understood that certain features and subcombinations are of utility and may be employed without reference to other features and subcombinations. This is contemplated by and is within the scope of our claims. It is further obvious that various changes may be made in details within the scope of our claims without departing from the spirit of our invention. It is, therefore, to be understood that our invention is not to be limited to the specific details shown and described.

Having thus described our invention, what we claim is:

1. A pouch for storing detonators including in combination an outer container, an inner flap fixed within said container, and a plurality of detonator carrying compartments mounted on said flap, said inner flap having a length sufficient to permit the flap to be wrapped around the compartments mounted thereon to aid in containing the explosion resulting from the accidental firing of a detonator, each of said outer container and flap and compartments being formed of ballistic material.

2. A pouch as in claim 1 in which said outer container includes a front and a cover formed with a portion overlying said front when said cover is in a closed position and means for securing said cover to said front.

3. A pouch as in claim 1 in which said inner flap is formed of ballistic material, and means for securing one end of said inner flap within said outer container, the other end of said inner flap being free for its removal from the outer container.

4. A pouch as in claim 1 including sleeves by means of which said detonators are carried in said compartments for ready removal therefrom.

5. A pouch as in claim 1 in which said ballistic material includes a plurality of fabric laminates, each of said laminates being formed of yarns made up of continuous synthetic filament threads spun to a predetermined number of convolutions per unit length.

6. A pouch as in claim 1 in which said ballistic material includes threads made up of continuous synthetic filaments, each of said threads being spun to a number of convolutions per unit length within the range of convolutions which corresponds to between fifty and ninety percent of the ultimate elongation of a filament.

7. A pouch as in claim 1 in which said ballistic material includes a plurality of stacked fabric laminates, each of said laminates being formed of yarns made up of continuous synthetic filament threads spun to a predetermined number of convolutions per unit length, and means for retaining said laminates in stacked relationship.

8. A pouch as in claim 1 including a carrying belt secured to said outer container and formed with a slot adjacent one end thereof, an eye carried adjacent the end of said belt remote from the slot, a shoulder strap fixed at one end to said belt, and a hook carried at the other end of said shoulder strap.

9. A pouch as in claim 1 wherein said outer container includes a pair of sides and a pair of pockets formed respectively at said sides.

10. A pouch for storing detonators including in combination an outer container, an elongated inner flap having a pair of ends, a plurality of detonator carrying compartments, means securing said detonator compartments to said elongated flap intermediate the flap ends, and means securing one of said flap ends within said container, said inner flap being adapted to be wrapped around said compartments for insertion within said container.
